UNITED STATES PATENT OFFICE.

WILLIAM WILLHEIM, OF NEW YORK, N. Y., ASSIGNOR TO FRANK & COHEN SILK CORPORATION, A CORPORATION OF NEW YORK.

DESIGN FOR A TEXTILE FABRIC OR SIMILAR ARTICLE.

Application filed October 26, 1928. Serial No. 28,644. Term of patent 3½ years.

To all whom it may concern:

Be it known that I, WILLIAM WILLHEIM, a citizen of the United States, residing at New York city, in the county of New York and State of New York, have invented a new, original, and ornamental Design for a Textile Fabric or Similar Article, of which the following is a specification, reference being had to the accompanying drawing and to the accompanying sample of goods bearing the design, forming a part thereof.

The figure on the drawing is a plan view

of a piece of textile fabric bearing my new design, a single repeat unit being comprised within the area defined by the indicating arrows. The shading on the drawing indicates more or less contrasting colors and does not necessarily indicate specific colors.

I claim as my invention:

The ornamental design for a textile fabric or similar article substantially as shown and described.

WILLIAM WILLHEIM.
